(57) **CLAIM**

I claim the ornamental design for a merchandise rack display system, as shown and described.

DESCRIPTION

FIG. 1 is an elevated perspective view of a merchandise rack display system showing my new design;

FIG. 2 is a frontal view thereof;

FIG. 3 is a right side view thereof;

FIG. 4 is a left side view thereof;

FIG. 5 is a rear side view thereof;

FIG. 6 is a top view thereof;

FIG. 7 is a bottom view thereof; and,

FIG. 8 is a top view thereof showing first and second rotatably mountable rack portions swung inwardly.
